CLAIM

The ornamental design for a utility light as shown and described.

DESCRIPTION

FIG. 1 is a perspective view of the utility light according to a first embodiment of the new design in an unfolded state; FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the utility light according to the first embodiment in an alternative folded state;

FIG. 9 is a front view thereof;

FIG. 10 is a rear view thereof;

FIG. 11 is a left side view thereof;

FIG. 12 is a right side view thereof

FIG. 13 is a top view thereof;

FIG. 14 is a bottom view thereof;

FIG. 15 is a perspective view of the utility light according to a second embodiment of the new design in an unfolded state;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is a bottom view thereof;

FIG. 22 is a perspective view of the utility light according to the second embodiment in an alternative folded state;

FIG. 23 is a front view thereof;

FIG. 24 is a rear view thereof;

FIG. 25 is a left side view thereof;

FIG. 26 is a right side view thereof

FIG. 27 is a bottom view thereof; and,

FIG. 28 is a top view thereof.

(Continued)

The broken lines shown in the drawings depict portions of the utility light that form no part of the claimed design.
